FOLDING CARTON AND BLANK THEREFOR
Charles R. Zeitter, Grand Rapids, Mich., assignor to
Packaging Corporation of America, Evanston, Ill., a
corporation of Delaware

Filed Oct. 21, 1965, Ser. No. 499,557
9 Claims. (Cl. 229—16)

ABSTRACT OF THE DISCLOSURE

A folding carton having opposed main front and back panels also has a central opening in which a housed product is readily observable. The blank from which the carton is formed possesses a plurality of foldlines and slits enabling three continuous side flaps to form a border for the central opening in combination with inner side flaps extending from peripheral portions of the main panels defining the opening; the continuous border also serving to maintain the main panels in spaced, parallel relationship.

This invention relates to a folding carton and blank therefor and more particularly to a carton wherein the product disposed therein is readily observable without the carton being opened.

Various cartons of this general type have heretofore been proposed; however, because of certain design characteristics, they are of a costly and complex construction, are unattractive in appearance, or are ineffective in providing adequate protection for the accommodated product.

Thus, it is one of the objects of this invention to provide a folding carton which is not beset with the aforementioned shortcomings of the prior art cartons.

It is a further object of this invention to provide a folding carton which may be formed from a blank of paperboard having printed indicia on only one surface thereof, whereby, when the carton is set up, only the printed surface of the blank is exposed.

It is a still further object of this invention to provide a folding carton which is sturdy and compact and capable of accommodating a variety of products notwithstanding that the blank for said carton is formed of relatively thin gauge paperboard stock.

It is a still further object of this invention to provide a folding carton which is capable of being set up manually or by automatic equipment.

Further and additional objects will appear from the description, accompanying drawings, and appended claims.

In accordance with one embodiment of this invention a folding carton is provided which comprises apertured front and back panels arranged in spaced registered relation. An aperture in one of the panels is in aligned position with respect to a corresponding aperture in the other panel. Outer side panels are provided which foldably interconnect corresponding peripheral portions of the front and back panels. Closure flaps are foldably connected to opposite ends of the front, back, and side panels and cooperate to effect closing of the carton ends. Corresponding perimetrical portions of the aligned apertures are interconnected by folding flaps, which delimit the aligned apertures.

For a more complete understanding of this invention reference should be made to the drawings wherein:

FIGURE 1 is a top plan view of one form of a blank for the improved carton;

FIG. 2 is similar to FIG. 1 but showing a modified blank;

FIGS. 3-5 are perspective views of the blank of FIG. 1 shown in various stages of setup;

2

FIG. 6 is a perspective view of the improved carton fully set up from the blank of FIG. 1;

FIG. 7 is similar to FIG. 6 but showing an improved carton fully set up from the blank of FIG. 2.

5 Referring now to FIG. 1 a blank 10 of thin gauge paperboard printed on only one surface thereof is shown which is adapted, when fully set up, to form the improved carton 11, shown in FIG. 6. The surface of blank 10 shown in FIG. 1 is the unprinted surface; however, as 10 will be hereinafter discussed, only the printed surface of the blank will be exposed when the carton is set up as shown in FIG. 6.

Blank 10 is provided with a plurality of foldlines and cuts which are adapted to cooperate with one another so 15 as to form a back panel 13 which is provided with an enlarged central opening 14. Connected by foldline 15 to a perimetrical segment of opening 14 is an inner flap 16, the function of which will be described more fully hereinafter.

20 Connected by a pair of spaced substantially parallel foldlines 17 and 18 to opposite sides of back panel 13 are side panels 20 and 21. When the blank is set up to form carton 11, panels 20 and 21 assume vertical positions with respect to back panel 13. Connected by foldline 22 25 to the opposite side of panel 20 is a front panel 23. Panel 23 is likewise provided with an enlarged central opening 24 which is similar in configuration to opening 14 formed in back panel 13. Connected by foldline 25 to a perimetrical segment of opening 24 is a second inner flap 26. The 30 configuration of flap 26 closely resembles that of flap 16, so that when the blank 10 is fully set up, flap 26 will overlie flap 16 and be adhesively affixed thereto. Thus, flaps 16 and 26 serve to retain the portions of the back and front panels circumjacent the central openings thereof in 35 proper spaced relation with respect to one another.

Connected by foldline 27 to the opposite side of panel 21 is a bridging panel 28. The function of panel 28 will be discussed more fully hereinafter. Connected to the 40 opposite side of panel 28 by foldline 30 is a third inner flap 31 which is adapted to interconnect other corresponding perimetrical segments of openings 14 and 24, when the blank is set up to form carton 11. Foldline 30 is shorter than foldline 27 and is approximately equal in length to perimetrical segment 14a of opening 14.

45 Connected by foldline 32 to the outer edge of flap 31 is an anchoring flap or panel 33. Flap 33 is adapted to be adhesively affixed to the unprinted surface of back panel 13 when the carton 11 is formed. Foldline 32 is disposed in coincident relation with respect to perimetrical segment 14a of opening 14. FIG. 3 shows the disposition of 50 the third inner flap 31 to be perpendicular to back panel 13.

Foldably connected to opposite ends of third inner flap 31 are fourth and fifth inner flaps 34 and 35, respectively, 55. Each flap 34 or 35 is provided with foldable side and end tabs 34a and 34b, and 35a and 35b. As seen in FIG. 4, during setting up of the blank 10, fourth and fifth inner flaps 34 and 35 and their associated side and end tabs are folded at right angles with respect to third inner flap 31, so that flap 31 is coincident to opening segment 14a, flap 34 is coincident to perimetrical segment 14b of opening 14, and flap 35 is coincident to perimetrical segment 14c of opening 14. Tabs 34a-b and 35a-b, in turn, 60 are folded at right angles to flaps 34 and 35, respectively, see FIG. 4. The folded flaps normally are disposed in frictional face-to-face relation with respect to the unprinted or concealed surfaces of back and front panels 13 and 23 and side panel 20, when the carton 11 is erected.

As seen in FIG. 1, side panels 20 and 21 are provided with end closure flaps 36 and 37, respectively. Flaps 36 and 37 are adapted to cooperate with closure flaps 38

and 40 foldably connected to opposite ends of front or top panel 23. Flaps 38 and 40 are each provided with a tuck flap 38a and 40a which are adapted to be tucked between flaps 34a and 35a and the unprinted surface of back panel 13, when the blank 10 is set up to form carton 11.

Carton 11 is of a structure suitable for hanging on a display rod. To facilitate the hanging thereof, back panel 13 is provided with tongue portion 13a having the upper section 13b thereof adapted to be folded over so as to provide a two-ply thickness. Portion 13a and section 13b are provided with openings 13c which are in registration with one another when section 13b assumes its folded position. Section 13b may be retained in its folded position by either adhesively affixing section 13b to portion 13a or by having the distal edge of section 13b tucked behind tuck flap 38a of end closure flap 38.

When the blank 10 is set up to form carton 11, openings 14 and 24 are in registered relation. It is in the open center part of the carton that the product to be packaged is disposed. The size and shape of openings 14 and 24 and the size and shape of the inner flaps will depend upon the product to be packaged. If, for example, the product in question was a padlock, not shown, the hasp thereof might project into a suitable slot 41, shown in dotted lines, provided in inner flap 34, see FIG. 1. Likewise a slot 42, shown in dotted lines, might be provided in inner flap 35 which might frictionally accommodate the bottom portion of the lock housing. On the other hand, if the product is a bottle, not shown, which has a neck portion, then the slot 41 would be sized to frictionally accommodate said neck portion. Slot 42 in a like manner would be sized to accommodate the base or bottom portion of the bottle. Because of the frictional engagement between the product and the inner flaps no additional securing means is required. However, if desired, the center portion of the carton may be overwrapped by a clear plastic film or the product may be further retained in place by spotgluing.

FIG. 2 discloses a modified carton blank 43 which is similar in many respects to blank 10. Because of this fact and in order to simplify understanding of the structure of blank 43, similar numbers, but in the one hundred series, will be utilized. Back panel 113 and front panel 123 are similar in configuration to panels 13 and 23 of blank 10 except that the opening 114 is provided with two inner flaps 116 and 119 foldably connected to opposite perimetrical segments of the opening. In addition the hanger tongue portion 13a and section 13b has been eliminated in blank 43; however, the elimination thereof is optional.

It will be noted that the fourth and fifth inner flaps 134 and 135, respectively, which are foldably connected to opposite ends of third inner flap 131, each have only one side flap 134a or 135a connected thereto. In addition, anchoring flap 33 of blank 10 has been eliminated in blank 43. The reason for flap 33 being eliminated is that inner flap 119 disposed in opening 114 is adapted to be adhesively affixed to third inner flap 131 when blank 43 is set up to form carton 44, shown in FIG. 7. By eliminating the various tabs, tongues, and flap aforesaid in blank 43, substantial savings in material may be effected when forming a plurality of blanks from a web of paperboard or the like.

In setting up blank 10, side panel 21 is folded to an upright position with respect to back panel 13. Bridging panel 28 and inner flap 31 are then folded relative to panel 21 so as to assume respective horizontal and vertical positions, see FIG. 3. Anchoring flap 33 has adhesive applied to the back surface thereof. Whereupon the anchoring flap 33 being folded at a right angle to flap 31, the coated surface of flap 33 will bond with the unprinted surface of back panel 13 between perimetrical segment 14a and foldline 18. It should be noted that anchoring flap 33 is separated from side tabs 34a and 35a by slits or cuts. In securing anchoring flap 33 to the back panel 13,

it is important from an appearance standpoint that foldline 32 be made coincident with perimetrical segment 14a.

With blank 43, in place of adhesively securing an anchoring flap to the back panel, inner flap 119 is adhesively coated on one surface thereof, whereupon flap 131 is brought into adhesive engagement with the coated surface of folded flap 119.

As shown in FIG. 4, the fourth and fifth inner flaps 34 and 35 and their respective tabs 34a-b and 35a-b are folded relative to flap 31 so as to assume the positions shown. When disposed, as seen in FIG. 4, flaps 34 and 35 are aligned with perimetrical segments 14b and c, respectively, of opening 14.

Side panel 20 is then folded upright and front panel 23 is folded at a right angle thereto so as to assume a superimposed position with respect to back panel 13. The portion 23a of the front panel overlies and is adhesively affixed to bridging panel 28, so that blank 10 assumes the condition shown in FIG. 5. Prior to the blank assuming the condition of FIG. 5, the product to be packaged may be located between the fourth and fifth inner flaps.

The closure flaps, as shown in FIG. 5 are then folded relative to one another to close the ends of the carton. Section 13b may then be folded relative to tongue portion 13a.

As aforesaid, carton 11 or 44 has all the exposed surfaces thereof formed by the printed surface of the blank 10 or 43. Thus, it is necessary that the blank have only one printed surface. Furthermore, the various panels, flaps, tabs, and portions cooperate with one another to form a very strong and sturdy carton, notwithstanding the caliper of the material used.

Various modifications besides those shown and discussed may be made with regard to the shape and size of the various panels and the openings in the front and back panels. Furthermore, if in certain instances, appearance in so far as exposure of the unprinted surface of the blank is not important, then fourth and fifth inner flaps 34 and 35 or 134 and 135 and their associated tabs might be eliminated entirely.

While several embodiments of this invention have been described above, further modifications may be made thereto and it is contemplated, therefore, by the appended claims, to cover any such modifications as fall within the true spirit and scope of this invention.

I claim:

1. A blank of sheet material for use in forming a foldable carton having front and back panels provided with aligned enlarged openings, said blank having a plurality of foldlines and slits cooperating with one another to form a back panel having an enlarged opening formed therein, at least one inner side flap, foldably connected to a peripheral segment of said opening, outer side panels foldably connected to opposite peripheral portions of said back panel, a front panel foldably connected to a peripheral portion of one of said outer side panels opposite the peripheral portion to which said back panel is connected, said front panel being provided with an enlarged opening, a second inner side flap foldably connected to a peripheral segment of the front panel opening, said second inner side flap being adapted to be adhesively secured to said one inner side flap when said blank is set up to form said carton, a bridging panel foldably connected to a peripheral portion of the other of said outer side panels opposite the peripheral portion to which said back panel is connected, a third inner side flap foldably connected to a peripheral portion of said bridging panel opposite to that connected to said other outer side panel; said third inner side flap being adapted to span the interval between the front and back panels and comprise a border portion defining said central openings in said front and back panels when said blank is set up to form said carton, the foldline connection between said bridging panel and said other outer side panel being of greater extent than the foldline connection between said bridging panel and said

third inner flap, and closure flaps foldably connected to opposite ends of said outer side panels and said front panel.

2. A folding carton comprising a front panel, a back panel disposed in spaced registered relationship with respect thereto, said front and back panels each being provided with a large aligned opening, first outer side panels interconnecting corresponding peripheral portions of said front and back panels, a bridging panel foldably engaging an edge portion of one of said first outer side panels, the later foldable engagement being disposed parallel to the edge portion of said one outer side panel in foldable engagement with said back panel, a third inner side flap foldably connected to an edge portion of said bridging panel in parallel relationship with the bridging panel foldable connection with said one outer side panel; said third side flap being foldably connected to fourth and fifth side flaps at opposed end limits along foldlines transversely disposed to the third inner side flap foldable connection with said bridging panel; said, third, fourth and fifth side flaps spanning the interval between said front and back panels, and oppositely-disposed, adhesively-engaged flaps extending from peripheral portions of said aligned openings spanning the interval between said front and back panels and defining the periphery of said panel openings with said third, fourth and fifth side flaps.

3. The folding carton of claim 2 in which said third, fourth and fifth side flaps have side tabs extending from peripheral portions of said side flaps defining said panel openings and in engagement with peripheral portions of said front and back panels defining said aligned openings.

4. The carton recited in claim 2 including a hanger flap extending laterally outwardly from the periphery of said back panel.

5. A blank of sheet material for use in forming a foldable carton having front and back panels provided with aligned enlarged openings, said blank having a plurality of foldlines and slits cooperating with one another to form a back panel having an enlarged opening formed therein, a first inner side flap foldably connected to a peripheral segment of said opening, outer side panels foldably connected to opposite peripheral portions of said back panel, a front panel foldably connected to a peripheral portion of one of said outer side panels opposite the peripheral portion to which said back panel is connected, said front panel being provided with an enlarged opening which is adapted to assume a spaced registered relation with respect to said back panel opening when said blank is set up to form said carton, a second inner side flap foldably connected to a peripheral segment of said front panel opening, said second inner side flap being adapted to be adhesively secured to said first inner side flap when said blank is set up to form a carton, a bridging panel foldably connected to a peripheral portion of said other outer side panel opposite the peripheral portion to which said back panel is connected, said bridging panel being adapted to be adhesively connected to the concealed surface of said front panel when said blank is set up to form said carton, a third inner side flap foldably connected to the opposite side of said bridging panel, the foldline connected between said bridging panel and said other outer side panel being of greater extent than the foldline connection between said bridging panel and said third inner flap, an anchoring tab foldably connected to the opposite side of said third inner side flap, said anchoring tab being adapted to be adhesively affixed to the concealed surface of said back panel when said blank is set up to form a carton, fourth inner side flap foldably connected to one end of said third inner side flap, fifth

inner side flap foldably connected to the opposite end of said third inner side flap, said side flaps cooperating with one another to delimit the registered central openings and span the distance between said front and back panels when said blank is set up to form said carton, second anchoring flaps foldably connected to said fourth and fifth inner side flaps, and closure flaps foldably connected to opposite ends of said outer side panels and said front panel.

10 6. The blank recited in claim 5 including a hanger flap foldably connected to one end of said back panel.

7. A blank of sheet material for use in forming a foldable carton having front and back panels provided with aligned enlarged openings, said blank having a plurality of foldlines and slits cooperating with one another to form a back panel having an enlarged opening formed therein, first inner side flaps foldably connected to opposite peripheral segments of said opening, outer side panels foldably connected to opposite peripheral portions of said back panel, a front panel foldably connected to a peripheral portion of one of said outer side panels opposite the peripheral portion to which said back panel is connected, said front panel being provided with an enlarged opening, a second inner side flap foldably connected to a peripheral segment of said front panel opening, said second inner side flap being adapted to be adhesively secured to one of said first inner side flaps when said blank is set up to form said carton, a bridging panel foldably connected to a peripheral portion of said other outer side panel opposite the peripheral portion to which said back panel is connected, said bridging panel being adapted to be adhesively connected to the concealed surface of said front panel when said blank is set up to form said carton, a third inner side flap foldably connected to the opposite side of said bridging panel, said third inner side flap being adapted to be adhesively connected to the other of said first inner side flaps, when said blank is set up to form said carton the foldline connection between said bridging panel and said other outer side panel being of greater extent than the foldline connection between said bridging panel and said third inner flap, and closure flaps foldably connected to opposite ends of said outer side panels and said front panel.

45 8. The blank recited in claim 7 including a fourth inner side flap foldably connected to one end of said third inner side flap, a fifth inner side flap foldably connected to the opposite end of said third inner side flap, said side flaps cooperating with one another to delimit the aligned openings and span the distance between said front and back panels when said blank is set up to form said carton, and anchoring flaps foldably connected to said fourth and fifth inner side flaps.

50 9. The blank recited in claim 7 including a hanger flap foldably connected to one end of said back panel.
